UNITED STATES PATENT OFFICE.

ADOLPH TULOWITZ, OF DETROIT, MICHIGAN.

OIL-TEMPERATURE CONTROL FOR INTERNAL-COMBUSTION ENGINES.

Application filed September 2, 1927. Serial No. 217,292.

The present invention relates to engines, and more particularly to engines of the internal combustion type, provided with the usual crank case and oil pan from which oil is circulated or otherwise passed to parts of the engine requiring lubrication.

An object of the invention is to provide means for controlling the temperature of the oil, so that it may have the desired viscosity.

In the usual internal combustion engine, the oil is considerably heated, particularly in warm weather, by engagement with the cylinder walls, etc., and the oil being repeatedly circulated through the engine, without means for cooling the same, is continually maintained at a considerable degree of heat. This results in the thinning of the liquid, reduction in its lubricating efficiency, and the necessity for frequently replacing the same with fresh oil. When the temperature lowers, as in winter, the oil becomes relatively thick, particularly after the engine has remained idle for a considerable period, and, as a consequence, the lubricating effect of the oil is considerably reduced until it has become heated by operation of the engine. Without means for heating this oil, other than contact with the moving parts of the engine, the latter must operate for a considerable period with a materially impaired lubricating system, due to the thickness of the oil and its poor circulation.

An object of the invention is to provide means adapted for use with the usual internal combustion engine, which will control satisfactorily the oil temperature. The invention has as an object, the provision of automatic means responsive to the oil temperature for regulating the operation of the cooling and heating mechanism, as well as an auxiliary manually operable means, which may be used in case of emergency.

In the drawings:—

Figure 1 is a side elevational view,

Figure 2 is a fragmentary vertical sectional view on substantially the line 2—2 of Figure 1,

Figure 3 is a fragmentary vertical section taken through the exhaust pipe and the valve mechanism,

Figure 4 is a horizontal sectional view, and

Figure 5 is a fragmentary front elevational view.

Referring to the accompanying drawings, wherein there is shown a preferred embodiment,

10 indicates the usual internal combustion engine, having a crank case 11 adapted to contain oil up to the normal level indicated by the dotted line 12 in Figure 2. 60

The motor is provided with the exhaust pipe 13 adapted to direct the heated exhaust gases from the motor in the direction indicated by the arrow 14 in Figure 1.

Within the crank case is arranged a tortuous passage exemplified by the substantially U-shaped coil 15, one end 20 of which is connected by an elbow 21 with a branch 22 of a sleeve 23 encircling the exhaust pipe. The exhaust pipe is provided with a 70 lateral opening 24, through which exhaust gases may be directed by means of a valve 25 when the latter is in the full-line position indicated in Figure 3, the valve being mounted upon a rock shaft 26. A second 75 branch 27 connected to the sleeve 23 contains a valve 28 mounted upon a rock shaft 29, the rock shafts 26 and 29 being connected by link 30, which at its ends is secured to arms 31 upon the rock shafts. The 80 link is arranged so that when the valve 25 is open, so as to direct gases through the elbow 21 and passage 15, they will impart a substantial amount of heat to the oil within the crank case, and the amount of the 85 heat radiated may, of course, be increased by lengthening the passage 15.

The gases, after traveling through the heating passage 15, are discharged through an outlet funnel 32, which is directed forwardly for a purpose later to be described. The funnel is connected with the end 15' of the coil 15, by means of a rearwardly and downwardly and then upwardly directed elbow 33, which is provided at its lowermost portion with an opening 34, so that if water or sediment should enter the funnel 31 as the vehicle moves, it will gravitate through the opening 34, and not pass into the passage 15. 100

When the valve 25 is moved to the dotted line position indicated in Figure 3, in which it does not obstruct the passage of the exhaust gases through the exhaust pipe, the valve 28 will be open. These positions of the valves permit the air which is collected by the funnel 32, as the vehicle moves forwardly, to pass through the passage 15, and then be discharged through branch 27. A considerable volume of air will thus be directed through the passage, and its force will be increased by the suction created at 105 110

the rearwardly disposed branch 27. As the vehicle moves, the force of air passing the open end of branch 27 will create a considerable suction within the branch and passage 15, thus assisting in conducting the air, as a cooling medium, through the crank case passage 15. A strainer 35 may be provided within the funnel 32 to prevent ingress of solid particles which might clog or obstruct 10 the cooling passage. Dust and other fine particles will settle within the gooseneck or elbow 33, and gravitate to the opening 34.

Any suitable means may be provided for actuating the valves, such as, for instance, 15 the manually operable rod 37 connected by means of arm 38 with the extended end of the rock shaft 29. In addition to this manually controlled operable means, however, it is desirable to provide automatic means responsive to the oil temperature. For instance, a thermostat mechanism 40, having a portion 41 projecting into the oil within the crank case, may be connected by means of a rod 42 with an upwardly projecting arm 43 25 on shaft 29, so that as the temperature of the oil varies, the valves 25, 28 may be moved between their positions illustrated in Figure 3.

Obviously, the construction disclosed may 30 be varied considerably without departing from the invention, the essence of which consists in providing means selectively operable for passing either a heating medium or a cooling medium in proximity to the oil, 35 preferably, when in the crank case. Various modifications of the structure illustrated will suggest themselves to one skilled in the art, all of which are within the scope of the invention, as defined by the following 40 claims.

I claim:

1. In combination with an internal combustion engine having a crank case adapted to contain oil, means forming a passage in 45 the crank case excluded from the oil, said passage being disposed below the normal oil level, whereby a medium passed therethrough may be substantially surrounded by the oil, and means operable selectively to direct either an oil heating medium or an oil cooling medium through said passage and below the normal oil level, whereby to control the temperature of the oil in the crank case.
2. In combination with an internal combustion engine having a crank case, means 50 operable selectively to direct either an oil

heating medium or an oil cooling medium in proximity to the oil in said crank case, means responsive to the oil temperature for 60 automatically controlling the selective operation of said first mentioned means, and manually operable means for controlling the selective operation of said first mentioned means.

3. In an internal combustion engine provided with the usual oil containing crank case, a means having tortuous passage extending through a portion of said crank case below the normal oil level, so as to be 70 normally submerged in the oil, and means operable selectively to direct either the exhaust gases or a cooling medium through said passage whereby to control the temperature of the oil in the crank case.

4. In an internal combustion engine provided with the usual oil containing crank case, means having a tortuous passage extending through a portion of said crank case below the normal oil level so as to be 75 normally submerged in the oil, and means automatically operable selectively to direct either the exhaust gases or a cooling medium through said passage whereby to control the temperature of the oil in the crank case.

5. In an internal combustion engine provided with the usual oil containing crank case, means having a tortuous passage extending through a portion of said crank case below the normal oil level so as to be 80 normally submerged in the oil, means operable selectively to direct either the exhaust gases or a cooling medium through said passage whereby to control the temperature of the oil in the crank case, and both automatically and manually operable means for controlling the selective operation of said 85 last mentioned means.

6. In a motor vehicle having an internal combustion engine provided with the usual 100 crank case, means having a tortuous passage extending through a portion of the crank case below the normal oil level so as to be normally submerged in oil, means operable to direct exhaust gases through said passage 105 to raise the temperature of the oil in the crank case, and means operable upon discontinuance of the passage of exhaust gases to permit a cooling medium to be directed through said passage.

In testimony whereof I have hereunto set my hand.

ADOLPH TULOWITZ.
